UNITED STATES PATENT OFFICE.

WALTER J. GADSBY, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 12,753, dated February 7, 1882.

Application filed January 12, 1882. Term of patent 31 years.

To all whom it may concern:

Be it known that I, WALTER J. GADSBY, of Boston, in the county of Suffolk and State of Massachusetts, have invented a new and original Design for Carpets, of which the following is a specification.

The nature of my design is fully shown in the accompanying photographic illustration.

The design is composed of the light ground 10 centers A F, each of substantially octagonal form, partially concealed by foliage and flowers, the smaller figures B C D E, arranged around the centers A, the similar figures G H I J, arranged around the centers F, and floral and foliage ornamentation interspersed between said figures, as shown.

I claim—

The design for a carpet, substantially as shown and described.

In testimony whereof I have signed my name 20 to this specification, in the presence of two subscribing witnesses, this 10th day of January, A. D. 1882.

WALTER J. GADSBY.
